FIG. 1 is a perspective view of a headset showing my new design viewed from rear bottom left;

FIG. 2 is perspective of FIG. 1 view viewed from rear top left;

FIG. 3 is a rear view thereof;

FIG. 4 is a bottom view thereof;

FIG. 5 is perspective view thereof viewed from front bottom left;

FIG. 6 is a perspective view thereof viewed from front top left;

FIG. 7 is a front view thereof;

FIG. 8 is a left side view thereof;

FIG. 9 is a right side view thereof; and,

FIG. 10 is a top view thereof.

The features shown in broken lines in the various Figures are for illustrating environmental structure and form no part of the claimed design.
